SANDING MACHINE FOR MOTOR VEHICLES

Rue Raymond Elston, Minneapolis, Minn., assignor to Highway Safety Appliances, Incorporated, St. Paul, Minn., a corporation of Minnesota

Application October 28, 1938, Serial No. 237,503

3 Claims. (Cl. 291—44)

This invention relates to improvements in sanding machines of the general type described in my Patents No. 1,812,521 dated June 30, 1931, for Sander for busses and other vehicles, and No. 2,016,419 dated October 8, 1935, for Sander for motor vehicles.

It is an object of this invention to provide a machine of this class having novel means for guarding against the freezing and clogging of the outlet passages for the sand when used under such conditions as freezing temperatures and spraying moisture.

Another object is to provide in a machine of this class outlet spouts for the sand adapted to be quickly and easily adjusted to properly distribute the sand in front of wheels of the double tire type wherein the widths of the tires and spacing of them transversely of the machine varies between wide limits.

20 A further object is to provide a machine of this class with a control valve for the sand and quickly adjustable means for regulating the degree of opening of the valve to meet the varying requirements for adequate and economical use 25 of sand or other gritty material.

Other objects will appear and be more fully pointed out in the following specification and claims.

Referring to the accompanying drawings: 30 Figure 1 is a side elevation of my improved sanding machine, together with a fragmentary portion of the vehicle on which it is mounted; Fig. 2 is a cross section through the vehicle frame taken on the line 2—2 of Fig. 1, showing 35 the sanding machine in front elevation;

Fig. 3 is a central vertical section through one of the stand outlet spouts;

Fig. 4 is a plan view of one of the sand hoppers;

Fig. 5 is a bottom view of the hopper and discharge portions of one of the sanding machine units, and

Fig. 6 is a vertical section through one of the hoppers, associated control mechanism and upper portions of the outlet spouts, taken on the line 45 6—6 of Fig. 5.

My improved sanding machine is particularly although not exclusively adapted for use with a motor vehicle of the type having double tired 50 wheels 7 and frame members 8. A pair of sand hoppers 9 are supported on a pair of angle bars 10 extending across the frame members 8 and secured thereto in suitable manner. The top of each hopper has a filling opening provided with 55 a hinged cover 11 adapted to be secured in closed

position by a bolt 12 and wing nut threaded thereon.

Mounted on the bottom of each of the sand hoppers 9 is a casting 13 communicating at its upper end with an opening in the bottom of the hopper and having short tubular outlets 14 at opposite sides. An annular valve seat 15 is provided near the upper extremity of the casting 13 and a conical valve closure 16 is fitted with an annular and resilient insert 17 to engage the valve seat. The closure 16 is secured to the upper end of a valve stem 18 which is arranged to be actuated to open the valve and a helical spring 19 is disposed coaxially with the stem 18 to normally hold the valve in closed position. The lower end of this spring abuts against a sealed cover 20 for a solenoid chamber 21 formed in the casting 13 between the outlets 14.

A solenoid coil 22 is enclosed in the chamber 21 with the stem 18 projecting into an axial opening in this coil and a tubular guide 23 projecting up from the cover 20 into the hollow valve closure 16 to exclude sand from the solenoid chamber. The lower end of the chamber 21 has an integral head 24 and threaded in a centrally located and tapped bore in this head is a stud 25 which projects into the path of the valve stem 18 to limit downward movement thereof. The position of the stud 25 is readily adjustable to regulate the valve opening, a kerfed end being exposed between the sand outlets 14. A lock nut 26 is threaded on the stud 25 and is also accessible to securely fasten the stud in adjusted position.

At one side the solenoid chamber 21 has an opening for electric circuit connections and the opening is normally closed by a plate 27 of insulating material. A terminal binding screw 28 projects from this plate for an external circuit wire 29 and this screw is included in one side of the circuit through the solenoid 22. The other side of the circuit is grounded on the casting 13.

To properly distribute the sand in front of the tires 7 of double tired wheels of various widths, I provide a pair of outlet spouts 30 constructed entirely from resilient flexible material, such as soft rubber. Each of these spouts has a cylindrical and vertically disposed upper end portion 31 which is fastened by a binding ring or clamp on the exterior of an outlet 14 of the casting 13. From the portion 31 each spout extends obliquely downward at an angle of approximately 45 degrees from the vertical and is formed with an enlarged, cylindrical and vertically disposed lower end portion 32 having the outlet opening in its

lower extremity. As best shown in Fig. 3, an annular shoulder 33 is formed within and in upwardly spaced relation to the lower end of the spout.

5 It has been found that this annular shoulder effectively guards against the clogging of the spout in operation because it deflects from the more restricted inner passage the spray of water which is produced when the vehicle is operating under 10 the adverse weather and road conditions requiring sanding. The spout 30 preferably has an opening or passage 34 through it of substantially cylindrical form and about one and one-half inches in diameter. Such bore is adequate to allow 15 the free flow of the sand at the desired rate but excludes a maximum of spray which if allowed to enter and collect in the spout causes clogging and freezing in the passage.

The solenoids 22 for a pair of the sanding machines are connected in a suitable circuit with the vehicle battery and this circuit includes a control switch, within convenient reach of the driver of the vehicle so that the latter can operate the sand valves instantaneously and simultaneously 25 when the sand is required to give improved traction. One suitable type of circuit for this purpose is described and illustrated in my Patent No. 1,812,521, above referred to and others will be obvious to those skilled in the art.

30 Sand of about one-quarter inch maximum screen or cinders or other suitable gritty material is charged into the hoppers 9 through the cover openings. When safe operation of the vehicle requires that the road be sanded the solenoids 22 are energized. This opens the valves by drawing the valve stems 18 downward and allows sand to flow from the hoppers 9 through the outlets 14 and spouts 30. These spouts properly distribute the sand in front of the wheels 7 as indicated in 40 Fig. 2. Various amounts of sand are required for different conditions and for wheels of different widths and sizes and the readily accessible stud 25 and lock nut 26 afford means for regulating the extent of the valve opening and corresponding rate of flow of the sand from the outlet spouts. In this manner I provide for the economical use of the sand or other gritty material carried in the hoppers 9.

By providing separate and independently adjustable outlet spouts 30, I adapt the machine for use where the spacing and size of the tires vary between wide limits and also make it possible to properly distribute the sand in various installations, such as those where the sand hoppers cannot be positioned directly in front of the wheels. With the long, laterally projecting spouts and their independent, rotary adjustment, the sand or other grit may be distributed to either side of the hopper and in streams at various distances 55 apart.

60 My elongated, flexible and laterally projecting spouts perform the further important function of preventing the adherence of water and snow and the formation of ice in and around the discharge openings. Experience has shown that where a part made of metal or other heat conducting material is located within or adjacent to the outlet opening of the spout relatively rapid freezing on of the water and clogging results. 65 This is avoided by my soft rubber spouts which are poor conductors of heat. When the vehicle is in motion the laterally projecting, free ends of the flexible spout are maintained in continuous, relatively violent vibration and this aids in preventing 70 the adherence of drops of water for a sufficient

time for the freezing on in detrimental quantities. The annular shoulders 33 in the spouts also guard against the clogging by freezing as hereinbefore described.

Having described my invention, what I claim as new and desire to protect by Letters Patent is:

5 1. In a sanding machine for motor vehicles of the double tire type said machine having a hopper for granular material, duplicate outlet passages communicating with the bottom of said hopper and having horizontally spaced and substantially horizontally disposed cylindrical discharge ends, and a valve controlling the flow of material from said hopper to said passages, the improvements which comprise separate flexible tubular spouts 10 projecting obliquely down and laterally from said passages to discharge independent and separate streams of said material, said spouts having cylindrical upper ends revolubly fitting the discharge ends of said passages whereby said spouts are 15 adapted to deliver streams of said material directly in front of vehicle tires variously spaced relative to each other and to the hopper, means securing the upper ends of said spouts to the discharge ends of said passages respectively, and an 20 annular internal shoulder formed in each of said spouts in upwardly spaced relation but adjacent to the lower discharge ends of the spouts, each of said spouts and shoulders being formed from 25 soft rubber and being freely supported whereby 30 the shoulder and lower end of each spout will vibrate when the vehicle to which the machine is attached is in motion to prevent adherence of moisture particles in the lower ends and shoulder portions of the spouts.

35 2. In a machine of the class described having a hopper for granular material, an outlet passage communicating with the bottom of said hopper and a valve controlling the flow of material from said hopper to said passage, the improvements 40 which comprise, a flexible tubular spout projecting obliquely down and laterally from said passage and adapted to conduct a stream of said material to a point of discharge substantially below said bottom, said spout having a substantially vertically disposed discharge outlet and an annular internal shoulder formed in the vertical portion 45 of said spout in upwardly spaced relation to the discharge outlet end of the spout, said spout and shoulder being formed from soft rubber and being 50 freely supported whereby the discharge end of the spout and shoulder will vibrate when the vehicle to which the machine is attached is in motion to prevent adherence of moisture particles in the discharge end and shoulder portion of the spout.

55 3. A sand discharge device for motor vehicle sanders comprising, a tube adapted for connection with a supply for sand, said tube comprising a flexible tubular spout for connection to said supply to project obliquely down and laterally 60 of said connection and adapted to conduct a stream of sand or the like to a point of discharge substantially below said supply, said spout having a substantially vertically disposed discharge outlet and an annular internal shoulder 65 formed in the vertical portion of said spout in upwardly spaced relation to the discharge outlet end of the spout, said spout and shoulder being formed from soft rubber and adapted to be 70 freely supported whereby the discharge end of the spout and shoulder will vibrate when the vehicle carrying the sander is in motion to prevent adherence of moisture particles in the discharge end and shoulder portion of the spout.
